UNITED STATES PATENT OFFICE.

HARRY W. HAMILTON, OF INDIANAPOLIS, INDIANA.

VACUUM POWER DEVICE.

1,219,938.

Specification of Letters Patent. Patented Mar. 20, 1917.

Application filed June 4, 1915. Serial No. 32,065.

To all whom it may concern:

Be it known that I, HARRY W. HAMILTON, a citizen of the United States, residing at Indianapolis, in the county of Marion and State of Indiana, have invented a new and useful Vacuum Power Device, of which the following is a specification.

It is the object of my invention to provide a power device which is actuated by a partial vacuum, and particularly to utilize the ordinarily wasted energy of the partial vacuum in the intake manifold of an internal combustion engine. It is my further object to utilize this energy for the purpose of pumping fuel to the carbureter of the engine, as the modern low-built automobile often precludes a gravity feed of the fuel to the carbureter.

In carrying out my invention, I provide a chamber having a movable wall, said chamber being connected through two valves to a partial vacuum, such as the intake manifold of an internal combustion engine, and to the atmosphere, respectively and connect such valves to said movable wall so that the movement of the wall to enlarge the chamber causes the opening of the valve connected to the partial vacuum and the closing of the valve connected to the atmosphere, and the movement of the movable wall to ensmall the chamber causes the closing of the first valve and the opening of the second valve. The movement of the movable wall causes the opening and closing of the valves, and the opening and closing of the valves causes changes in the pressure of the chamber, which changes in turn cause the moving of the movable wall in opposite directions. In the preferred form of my invention, the movable wall is in the form of a diaphragm, and in addition to furnishing the wall of the chamber already mentioned also furnishes a movable wall of another chamber which is connected through two automatic valves to a source of fuel supply and to a carbureter; so that as the diaphragm moves there is a pumping action to force the fuel from the source of fuel supply to the carbureter.

The accompanying drawing illustrates my invention. Figure 1 is a sectional view through a power device embodying my invention, showing diagrammatically its connections to an internal combustion engine,

a source of fuel supply, and a carbureter, the parts being in position to open the chamber of the power device to the intake manifold; Fig. 2 is a similar sectional view through this power device, but showing the chamber thereof closed to the intake manifold and opened to the atmosphere; and Fig. 3 is a detail showing the valves both in closed position, which occurs when the diaphragm is in an intermediate position and moving to enlarge the chamber.

An internal combustion engine 10, shown as having four cylinders, is shown diagrammatically as having the various cylinders connected to a common intake manifold 11, which in turn is connected by a supply pipe 12 to a carbureter 13. There is also a fuel supply tank 14, which has a filling cap 15 provided with a vent 16. All these are of any desired type, and the engine operates in the usual manner to maintain a partial vacuum in the intake manifold 11 and intake supply pipe 12.

The vacuum power device comprises a casing 20 which provides a chamber 21, one end of which chamber is provided with a movable wall, which in the preferred form of my invention is a flexible diaphragm 22. This diaphragm is clamped at its periphery between a flange 23 on the casing 20 and the rim of a cupped cover 24, which protects the diaphragm 22 and with it forms a second chamber 25, which is separated from the chamber 21 by the diaphragm 22 so that the two chambers are entirely distinct.

The chamber 21 is connected to the intake manifold 11 by a pipe 30, the entrance to which from the chamber 21 is in the form of a valve seat 31 which co-operates with a movable valve 32. This valve 32 is carried by a plunger 33, one end of which bears against the diaphragm 22. Preferably a spring 34 is provided for forcing the plunger 33 away from the valve seat 31. The valve 32 and plunger 33 are connected by a lost motion connection, which in the form shown is provided by a head 35 on the stem of the valve 32, this head being slidably mounted in a pocket 36 in the upper end of the plunger 33, and the head 35 being shorter than the pocket 36 so that the desired lost motion is provided. The plunger 33 is pivotally attached to the free end of an arm 37, the other end of which is pivot-

ally mounted on a lug 38 on the inner wall of the casing 20. The arm 37 is provided with a cross pin 39 at an intermediate point, which cross pin receives the slotted head 40 of a pin 41 slidably mounted in a bearing 42. The upper end of the pin 42 coöperates with a ball 43 of a ball valve, the seat of which is provided by a plug 44 having a screw-threaded mounting in the casing 20 so that it can be screwed in and out, a lock nut 45 being provided for clamping it in adjusted position. A perforated cap 46 is provided for retaining the ball 43.

In operation, the engine 10 maintains a partial vacuum in the intake manifold 11. The parts being in the position shown in Fig. 1, this partial vacuum causes the air within the chamber 21 to be drawn out past the valve seat 31 and through the pipe 30 into the intake manifold 11. The reduced pressure in the chamber 21 causes the rising of the diaphragm 22, which as it reaches the upper end of its movement causes the valve 32 to engage the valve seat 31 to close the outlet from the chamber 21, and also causes the pin 41 to lift the ball 43 from its seat to allow the ingress of air from the atmosphere into the chamber 21. This causes the pressure in the chamber 21 to be restored, whereupon the spring 34, assisted by the resilience of the diaphragm 22, returns such diaphragm to normal position, thus allowing the ball 43 to return to its seat, and then, after the lost motion provided by the head 35 and pocket 36 has been taken up, causing the valve 32 to be moved from its seat 31 to open the communication from the chamber 21 to the intake manifold. Then the operation just described is repeated.

The power produced by the movements of the diaphragm 22 may be used for any desired purpose. In the arrangement shown, this power is used for pumping fuel from the supply tank 14 to the carbureter 13. For this purpose, the chamber 25 is connected through a check valve 50 and a pipe 51 to the fuel supply tank 14, and through a check valve 52 and a pipe 53 to the fuel inlet of the carbureter 13. The check valve 50 opens toward the chamber 25, to permit fuel from the tank 14 to enter such chamber, while the check valve 52 opens away from such chamber, to permit the flow of fuel therefrom. Thus as the diaphragm is moved up and down as above described, the chamber 25 is alternately enlarged and ensmallled, and fuel from the tank 14 is first drawn into such chamber 25, through the valve 50, and then forced from such chamber to the carbureter 13, through the valve 52. The valve 52 being inverted, in the position shown, so that it will not drop to its seat by gravity, an actuating or setting spring 54 is provided for normally pressing it to its seat. The device is arranged to pump fuel at a greater

rate than is required by the carbureter, so as to furnish ample fuel at all times. The float valve in the carbureter acts to prevent any excess of fuel from being supplied to the carbureter. In the arrangement shown, the closing of the float valve in the carbureter merely blocks the outlet passageway from the chamber 25, and so stops the action of the device while the carbureter float valve is closed, by preventing the ensmalling of such chamber 25. This causes the action of the device and the supply of fuel to the carbureter to be intermittent. If it is preferred that the action of the device be continuous, there may be provided in the pipe 53 an overflow reservoir located at a higher level than the carbureter 13, the overflow pipe from said reservoir leading back to the supply tank 14.

I claim as my invention:

1. A vacuum power device, comprising a chamber having a movable wall, an outlet valve from said chamber for connection to a partial vacuum, an inlet valve leading from the atmosphere to said chamber, and connections from said movable wall to said two valves for closing the first valve and opening the second valve by the movement of said wall to ensmall the chamber and for opening the first valve and closing the second valve upon the movement of said wall to enlarge the chamber, said connections including a lost motion connection between the movable wall and the first valve for delaying the opening of such valve.

2. A vacuum power device, comprising a hollow casing, a flexible diaphragm closing said casing to provide a closed chamber therein, an outlet valve from said chamber for connection to a partial vacuum, an inlet valve connecting said chamber with the atmosphere, a spring tending to move said diaphragm in the direction to enlarge said chamber, and connections between said diaphragm and said two valves for closing the first valve and opening the second upon the flexing of the diaphragm inward and for opening the first valve and closing the second upon the flexing of the diaphragm outward relative to such chamber, said connection between the diaphragm and the first valve including a lost motion connection which permits the opening of said first valve to be delayed until after the outward flexing of the diaphragm has been partly completed.

3. A vacuum power device, comprising a hollow casing, a flexible diaphragm closing said casing to provide a closed chamber therein, an outlet valve from said chamber for connection to a partial vacuum, an inlet valve connecting said chamber with the atmosphere, and connections between said diaphragm and said two valves for closing the first valve and opening the second upon

the flexing of the diaphragm inward and for opening the first valve and closing the second upon the flexing of the diaphragm outward relative to such chamber, said connection between the diaphragm and the first valve including a lost motion connection which permits the opening of said first valve to be delayed until after the outward

flexing of the diaphragm has been partly completed.

In witness whereof, I have hereunto set my hand at Indianapolis, Indiana, this 17th day of May, A. D. one thousand nine hundred and fifteen.

10

HARRY W. HAMILTON.
